CLAIM

The ornamental design for a vehicle headlight, as shown and described.

DESCRIPTION

FIG. 1 is a perspective view of a vehicle headlight;

FIG. 2 is a front view thereof;

FIG. 3 is a side view thereof; and,

FIG. 4 is a top view thereof.

The drawings and descriptions disclose a first embodiment showing a left side and the claim includes a mirror image embodiment. The broken lines in the drawings are included to show environment and form no part of the claimed design.
